UNITED STATES PATENT OFFICE.

JOE MARTIN JEZ, OF THRALL, TEXAS, ASSIGNOR OF ONE-HALF TO CRAIG O. BLACK,
OF THRALL, TEXAS.

COTTON-PICKER'S SACK.

Application filed August 11, 1923. Serial No. 656,824.

To all whom it may concern:

Be it known that I, JOE MARTIN JEZ, a citizen of the United States, residing at Thrall, in the county of Williamson and 5 State of Texas, have invented new and useful Improvements in Cotton-Pickers' Sacks, of which the following is a specification.

This invention relates to improvements in cotton pickers' sacks, and its primary object is to provide simple, reliable and efficient means for strengthening and reinforcing the sack and protecting the same from wear by frictional contact with the person of the picker and by contact with the 15 ground, cotton stalks or other extraneous objects with which the sack may come in contact in the cotton field or while in course of transportation from place to place.

A still further object of the invention is 20 to provide a cotton picker's sack having strengthening and protecting means including a metallic shield plate detachably secured upon the rear side of the sack so as to lie between the same and the ground, and 25 constructed and arranged to shield the sack from wear by contact with the ground and also to protect the sack from injury by contact with extraneous objects, said shield being detachably supported in position so 30 as to admit of its ready and convenient removal when occasion requires.

The invention consists of the features of construction, combination and arrangement of parts, hereinafter fully described and 35 claimed, reference being had to the accompanying drawings, in which:—

Figure 1 is a rear elevation of a cotton picker's sack embodying my invention.

Figure 2 is a similar view of a portion of 40 the sack showing the protector flap in normal position.

Figure 3 is a view of a portion of the front side of the sack showing the transverse connecting strap thereon.

45 Referring now more particularly to the drawings, 1 designates a cotton picker's sack, made of any suitable strong and durable fabric and of oblong rectangular form, as is customary, said sack having an 50 upper open end or mouth portion 2 and a lower closed end or bottom portion 3. The sack is provided at its upper end with a shoulder strap 4 whereby it is supported upon the person of the picker while in use.

55 As is well known, sacks of this character

are subjected to a high degree of wear and tear, owing to their motions during the process of picking, through rubbing contact with the ground, as well as by contact with the cotton stalks, trash or other extraneous objects in the field. I thus provide means whereby the sack may be shielded and protected to a large extent from wear, tear and injury.

For the purposes described, I provide a 60 metallic shield 5, which is disposed upon the rear side of the sack, said shield being approximately of oblong rectangular form. The shield is arranged in practice to lie in contact with the rear wall of the sack, with 65 its upper edge lying somewhat below the horizontal transverse center of the sack and its lower edge projecting a greater or less distance below the bottom 3 of the sack. The shield may be made of galvanized sheet 70 metal of a desired thickness and of a width to extend approximately across the entire rear surface of the sack.

For supporting the shield in position, I provide said shield along its upper edge 80 with three equidistantly arranged openings 6, the central opening being disposed at the center of the sack and the other openings equidistantly on opposite sides thereof, which 85 openings are adapted to receive snap fasteners 7 upon a similar number of suspending straps 8. These straps are sewed or otherwise secured to the rear wall of the sack at or above the horizontal transverse center thereof and suspend the shield in working 90 position in an obvious manner. A transverse strap 9 is sewed or otherwise secured to the front of the sack and is provided at its ends with snap hooks 10 or other suitable 95 connectors, hinged or otherwise flexibly connected with the strap 9, so that they may be swung back against the rear side of the sack. Diametrically disposed openings 11 are provided in the shield at or about its transverse center to receive the snap hooks or connectors 10, whereby the shield 5 and strap 9 are 100 coupled to strengthen and reinforce the sack against pressure strains and liability of bursting when heavily filled. This connecting means between the strap and the shield further serves to prevent the shield from 105 swinging sidewise on the straps 8 and thereby hold the shield from lateral or sidewise deflection or displacement. The shield 5 may lie at a distance from the rear surface of 110

110

the sack, and the flexible connection afforded between the front wall of the sack through the medium of the strap 9 and pivoted connectors 10 adapts the sack to be filled to a maximum degree without interference, while at the same time the sack will be reinforced against any tendency to become unduly strained or to burst under pressure of a full load of cotton therein.

10 The sack is provided upon its rear side with a reinforcing and protecting strip 12 of heavy fabric sewed or otherwise secured thereto, and against which strip the straps 8 and their connectors and the upper edge of 15 the shield 5 are arranged to bear. This strip 12 serves to protect the sack from undue wear from the movements of the parts referred to when the sack is in service. A flap 13 is also provided upon the rear side 20 of the sack to cover the straps 8 and the connectors 7 and the upper edge portion of the shield 5. This flap is formed of heavy fabric, leather or other suitable material, sewed or otherwise secured at its upper half 25 along its longitudinal and side edges to the rear wall of the sack, leaving the lower half of said flap free so that it may be swung upwardly to expose the parts 7 and 8 for connection or disconnection of the shield 5 when occasion requires, and so that said flap 30 may be turned down to overlie the said parts when the sack is in service, as shown in Figure 2. This flap 15 serves the double function of protecting the sack from undue wear by contact with the upper edge 35 of the shield 5 and the ground, the straps 8 and the connectors 7, and also serves to prevent cotton stalks, trash or other extraneous objects coming in contact with the parts 40 7 and 8 and becoming entangled therein and causing disruption of said parts, or the col-

lection of such stalks and trash between the shield and the sack, while the sack is being transported through the field or dragged over the surface of the ground in its various 45 manipulation.

From the foregoing description, taken in connection with the drawings, it will be seen that my invention provides a cotton picker's sack embodying means, of a simple, reliable 50 and efficient character, for reinforcing and shielding the sack against undue wear and tear in service, and for performing other stated incidental functions, and that the construction is such as to adapt the shield plate 55 to be readily applied for use and removed whenever required for compact storage or shipment of the sack. Other advantages flowing out of the construction disclosed will be apparent from the foregoing description 60 and readily understood and appreciated by those versed in the art.

Having thus fully described my invention, I claim:

In a cotton picker's sack, the combination 65 of a bag or sack, a shield plate disposed upon the rear side thereof, flexible suspension devices secured to the rear side of the bag and detachably engaging the upper edge of the shield plate, a reinforcing band extending transversely across the front of the bag and provided with fastening members 70 detachably engaging the side edges of the shield plate, a wear strip positioned upon the rear face of the bag beneath the suspension devices and upper edge of the shield plate, and a flap secured to the rear side 75 of the bag and adapted to be turned down upon the flexible suspension devices and upper edge of the shield plate.

In testimony whereof I affix my signature.
JOE MARTIN JEZ.
